(57) **CLAIM**

The ornamental design for an accessory mounting anchor assembly, as shown and described.

DESCRIPTION

FIG. 1 is a perspective view of the hook portion of the anchor assembly of the present invention;

FIG. 2 is a top plan view of FIG. 1;

FIG. 3 is a bottom plan view of FIG. 1;

FIG. 4 is a rear view of FIG. 1;

FIG. 5 is a front view of FIG. 1;

FIG. 6 is a right side view of FIG. 1;

FIG. 7 is a left side view of FIG. 1;

FIG. 8 is a perspective view of the base portion of the anchor assembly of the present invention;

FIG. 9 is a top plan view of FIG. 8;

FIG. 10 is a bottom plan view of FIG. 8;

FIG. 11 is a rear view of FIG. 8;

FIG. 12 is a front view of FIG. 8;

FIG. 13 is a left side view of FIG. 8;

FIG. 14 is a right side view of FIG. 8;

FIG. 15 is a perspective view of the present anchor assembly with mirror and radar detector;

FIG. 16 is a rear view of FIG. 15;

FIG. 17 is a front view of FIG. 15;

FIG. 18 is a right side view of FIG. 15;

FIG. 19 is a left side view of FIG. 15;

FIG. 20 is a top plan view of FIG. 15; and,
